VEHICLE SPRING

Roy B. Simning, Minneapolis, Minn., assignor to
 Kynes Company, Minneapolis, Minn., a firm
 composed of Clement E. Nelson, George G.
 Kysor, and Roy B. Simning

Application November 25, 1932, Serial No. 644,310

3 Claims. (Cl. 267—38)

This invention relates to vehicle springs and has special reference to a compound spring assembly particularly adapted for use on a drop axle unit.

5 The principal object is to produce a more practical and dependable device of this character than heretofore known.

Another object is to produce such a device whereby no pivotal connections of the springs are 10 employed.

Still another object is to produce a more simple and practical form of spring securing means than heretofore known both within the shackles at the ends of the springs and centrally thereof.

15 Other objects and advantages of the invention will appear in the following description thereof.

Referring now to the accompanying drawing, forming part of this application, and wherein like reference characters indicate like parts:

20 Figure 1 is a side elevation of the springs as assembled showing all of the connections therewith in section; and Figure 2 is a vertical section on the line 2—2, Figure 1.

1 represents the stub axle, on the outer end 25 of which is mounted the single or dual wheel assembly as preferred, and which axle is rigidly fixed preferably as by shrinking within the unitary metal wheel block or bracket 2. This wheel block is made as narrow as practical and of sufficient length to properly support the springs one 30 above and one below the axle connection and also the transverse drop axle 3, the ends of which I prefer to have fixed as by shrinking within the lower extremities thereof.

35 The springs 4 and 5 are of the common multiple leaf type except as to their end connections within the chassis supporting blocks or brackets 6 and 7. These blocks are preferably of rectangular form and attached in any desired manner 40 to the chassis frame, each being provided with a rectangular notch or recess for reception of the ends of the spring, and in each notch or recess is installed a removable block, the ones for the ends of the lowermost spring being illustrated at 8 and 45 9 and the ones for the ends of the uppermost spring being shown at 10 and 11. Each of these blocks is held in position by a suitable bolt shown at 12 and the blocks 8 and 10 are stepped or notched in such a manner as to fairly snugly receive the bent down ends 13 and 14 of the second leaf, preferably, of the upper and lower springs respectively; that is, when the blocks 8 and 50 10 are drawn up tightly within their respective recesses: while the blocks 9 and 11 at the opposite ends of the springs are stepped in such

a manner as to provide room for free longitudinal movement of the springs, that is to a limited degree, and such space is clearly indicated at 15. This, as is obvious, provides ample end play for the springs and obviates the necessity of a rockable shaft such as commonly used.

The transverse openings in the wheel block 2 are of such a size as to snugly fit the springs with the exception as to the depth of said springs, they being sufficiently greater than the height of the 60 springs to permit in respect to the upper spring 5 of the insertion of the twin wedges 16 and in respect to the lower spring 4 the twin wedges 17; in the latter instance they being below the spring 65 and in the former being above the same; though either of the twin wedges may be located above or below its respective spring as circumstances 70 require and function equally well.

Now each pair of these wedges is held together by a through bolt 18 which is of the proper length 75 and provided with suitable nuts on one or both ends so that after being slipped in place in their contracted relation they may be drawn up and expanded by tightening of the bolt and thus insure a secure holding of the leaves of the springs together and the springs in the block, they, of course, each being provided with a suitable central tit or small through bolt, not shown, if desired.

In the preferred arrangement of assembly of 80 these springs it is considered desirable to so space the openings in the vehicle brackets 6 and 7 that the normal weight of the vehicle chassis will rest upon the lower or service spring with but little or no stress upon the upper, or what may be 85 termed the helper spring, so that as the load is increased, or vertical shock is experienced to the normal load, the helper spring will satisfactorily 90 function in taking its portion of the stress.

Characteristics of this novel assembly may be 95 enumerated as follows:

1st. The twin wedging of the springs within the unitary wheel block or bracket.

2nd. The union of both of the axles within the 100 block as by shrinking.

3rd. The holding of one pair of ends of the springs against longitudinal movement and providing for freedom of such action at the opposite ends.

4th. Ample provision for strength of the spring ends against torsional movement and freedom from distortion as occurs when shackle eyes are formed therein and providing two leaves instead of one for taking such stress.

Having thus described my invention, what I claim and desire to secure by Letters Patent, is:

1. A compound vehicle spring of the type described comprising a pair of leaf springs held in spaced relation one to another, fixed brackets at the opposite ends of the compound spring into which the opposite ends of the leaf springs extend, blocks for securely holding one pair of said ends in one of said brackets, and blocks for securely holding the opposite pair of ends in the other bracket but permitting some longitudinal movement of said springs therein.
2. A compound vehicle spring of the class described including a pair of leaf springs having bent ends and held in spaced relation to each other, a fixed bracket having openings therein at

either end of said leaf springs into which said ends extend, means for securing said bent ends in said openings, said means permitting longitudinal movement of one end of said springs to compensate for the spring action thereof.

3. A drop axle assembly for vehicles comprising a unitary wheel supporting block, a pair of springs rigidly held in spaced relation within said block, a wheel supporting stub axle extending laterally from said block, intermediate of said springs, a drop axle extending from the block in the opposite direction to said stub axle and beneath the springs, and means comprising unitary blocks for connecting the ends of the springs to a vehicle chassis.
